UNITED STATES PATENT OFFICE

2,552,482

VARIABLE RESISTANCE

Robert G. Ferris, Harvard, Ill., and James D. Jordan, Washington, D. C., assignors to the United States of America as represented by the Secretary of the Navy

Application June 24, 1944, Serial No. 541,990

8 Claims. (Cl. 102—70.2)

1

This invention relates generally to variable resistors, and particularly to an improved resistor construction for controlling the operation and response of electrical components mounted in a projectile, such as are provided; in certain types of fuzes.

One of the objects of the invention is to provide a variable resistor wherein the resistor element employed is completely coated with a protecting compound so that corrosion cannot occur during storage.

Another object of the invention is to provide a variable resistor having a contactor element which normally does not engage the resistance element, but which penetrates the protective coating to engage said resistance element and establish an electric circuit automatically upon the occurrence of setback when the projectile is fired.

Another object is to provide such a resistor which is easily adjustable from outside the projectile, is adapted to be used in controlling the action of a fuze, and is adjustable by turning a nose ring provided on the projectile in the usual manner, so that an electrical fuze equipped with the improved resistor may be adjusted by conventional fuze setting devices now in use.

A related object is to provide adjustable resistance means having the advantages last above outlined when employed in the controlling of a projectile fuze and which in addition, when so employed, constitutes a safety device maintaining the fuze in unarmed condition until the instant of firing.

Still further objects of the invention will appear as the description proceeds.

In the drawings:

Fig. 1 is a longitudinal sectional view of a projectile nose fuze incorporating a resistor constructed in accordance with this invention, certain of the fuze parts being illustrated only diagrammatically, and adjacent parts of a projectile to which the assembly is secured being also fragmentarily shown;

Fig. 2 is a side elevational view of the setting or adjusting ring;

Fig. 3 is a sectional view taken substantially on the line 3—3 of Fig. 1, and looking in the direction of the arrows;

Fig. 4 is an exploded view of the principal fuze parts, portions being broken away;

Fig. 5 is a fragmentary sectional detail taken substantially on the line 5—5 of Fig. 3 and looking in the direction of the arrows, showing on a larger scale the principal parts of the variable resistor construction;

Fig. 6 is a sectional detail upon a scale still larger than that of Fig. 5, showing the positions taken by the set-back-operable parts after firing; and

2

Fig. 7 is a detail sectional view taken substantially on the line 7—7 of Fig. 6, and looking in the direction of the arrows.

In the drawings similar numerals of reference will indicate like parts throughout the views.

The numeral 1 indicates generally a projectile the details of construction of which form no part of the present invention, but which is illustrated as formed with an internally threaded open forward end 2. Screwed in the open end and extending into the projectile is a can 3 having a flange mouth 4 overlying and forming a continuation of the forward end of the projectile 1. The mouth of the can is also counterbored or enlarged as at 5 to define a shoulder 6. Fitted in the can 3 is a receptacle 7 flared at its upper end at 8, to seat upon the shoulder 6. Through such flared or flanged portion 8 extend pins 9 for locking the receptacle in place.

Also fitted in the counterbored portion 5 is an adjusting ring 18 having an enlarged forward portion tapered conformably to the other parts and forming a further forward continuation of the fuze assembly. The adjusting ring is rotatably retained by a snap ring 19. The snap ring is accessible through a plurality of plugged openings 19a which permit compression of the snap ring and removal of the adjusting ring at will.

The fuze body 12 projects through the adjusting ring 18 and into the receptacle 7 and is held in place by a snap ring 11. A pin 27 in receptacle 7 projects into a slot 28 in the fuze body to lock the latter against rotating with the adjusting ring. The fuze body is provided with annular grooves near its midportion and underlying the adjusting ring, in which grooves the rings 13 and 14 are fitted. Ring 13 will hereinafter be identified as the resistance ring, or element, and may comprise a conventional coated or wire wound resistor, being shown as of the coated type. Over the resistance coating the element 13 is covered with lacquer to protect its surface from corrosive action. The ring 14, which will hereinafter be identified as the conductor ring, is also coated with lacquer or the like to protect its surface.

The forward section 15 is formed separately from the body section 12 and held thereto by a split ring 16.

The adjusting ring 18 is provided with a recess 21 which confronts the rings 13 and 14. Mounted in recess 21 are disks 22a, 22b, 23. Inner disk 23 constitutes a contact disk and is provided with a knurled or sharply serrated inner surface 24 which bridges and bears against the lacquered surfaces of rings 13, 14, the lacquered coatings normally preventing the establishment of an electrical connection between the rings by disk 23. Disks 22a and 22b constitute backing disks and are formed of plastic material. The disk 22b is peripherally flanged or cupped at 22c to receive

and position the contact disk 23, and complementary opposed grooves 22d, 22e are formed in disks 22a, 22b defining a passage, a continuation of which extends forwardly in ring 18. The entire passage thus formed is filled with lead, as indicated at 25.

In operation the resistance element 13 may be connected in an electric circuit with other components of a fuze designed for electrical operation in any desired manner. For example, the element 13 could be connected in a circuit in such manner that differences in the effective value of the portion of resistance ring in circuit would have the effect of changing the timing of the fuze, or the intensity of the influence required to detonate the fuze.

Fixed lugs, 10, 29, are provided, projecting rigidly from the fixed front flange 4 of the can and from the adjusting ring 18, respectively, to facilitate adjustment of the latter, and these lugs are so arranged as to permit adjustment of the ring 18 by any of the standard fuze setting means now in use for projectiles of similar class. The setting of the ring 18 may be calibrated in any suitable manner. It will be understood, however, that prior to firing of the projectile, the disk 23 is insulated from the ring 13 by the coating of lacquer. However, upon the occurrence of setback, when the projectile is fired, the lead 25 will be driven rearwardly by the force of setback, separating the disks 22a and 22b and driving disk 23 inwardly to force its knurled surface through the lacquer and into electrical contact with rings 13 and 14.

We claim:

1. In a fuze construction adapted at least partially for electrical operation, an electrical resistance element, an insulating and protective coating over said resistance element, a contact element adapted to engage the resistance element at any of a plurality of points to provide a selected electrical resistance but normally held from engagement with said resistance element by said coating, and means including a relatively massive portion actuatable by its inertia upon rapid acceleration of the projectile to fracture said coating and permit contact between said contact element and resistance element.

2. In a fuze construction adapted at least partially for electrical operation, a nose assembly including a body portion, an annular electrical resistance element coaxially carried by said body portion, a contact element rotatable around the axis of said nose assembly and including a relatively sharp part electrically engageable with said resistance element at any of a plurality of positions to provide a selected electrical resistance, an insulating and protective coating over said resistance element and normally preventing effective engagement between said contact element and resistance element, and means including a relatively massive portion actuatable by setback to force said contact element through said coating and into electrical connection with said resistance element.

3. In a fuze construction adapted at least partially for electrical operation, a nose assembly including a body portion, an annular electrical resistance element coaxially carried by said body portion, a contact element having a relatively sharp portion rotatable around the axis of said body portion and electrically engageable with said resistance element at any of a plurality of

positions to provide a selected electrical resistance, an insulating and protective coating over said resistance element and normally preventing effective engagement between said contact element and resistance element, means for rotating said contact element including a ring accessible from the exterior of the nose assembly, and setback operable means for forcing said sharp portion of the contact element through said coating and into electrical contact with said resistance element.

4. In a projectile fuze construction adapted at least partially for electrical operation, a nose assembly including a body portion, an electrical resistance element means including a movable contact for varying the effective portion of said resistance element, an insulating coating preventing electrical connection between said contact and resistance element, and setback operable means for driving said contact through said coating to establish electrical connection between the contact and resistance.

5. A projectile fuze construction as defined in claim 4 in which said setback-operable means comprises a metallic mass capable of plastic deformation at ordinary temperatures and positioned to be urged against said contact by setback.

6. A projectile fuze construction as defined in claim 4 in which said contact is movable in one direction to vary the value of the resistance adapted to become effective upon penetration of said coating, and movable in another direction to penetrate the coating.

7. A projectile fuze construction as defined in claim 4 in which said contact is movable in one direction to vary the value of the resistance adapted to become effective upon penetration of said coating, and movable in another direction to penetrate the coating, said setback-operable means comprising a mass of relatively heavy material adapted to bear against the contact to urge it in the first-mentioned direction upon setback.

8. A projectile construction as defined in claim 4 in which said contact is movable in one direction to vary the value of the resistance adapted to become effective upon penetration of said coating, and movable in another direction to penetrate the coating, said setback-operable means comprising a mass of metal capable of plastic deformation at ordinary temperatures by the force developed in setback and trapped in and filling a chamber communicating with said contact, a substantial proportion of said metal extending forwardly in the direction of intended projection of the projectile, whereby said metal may tend to flow and exert static pressure upon said contact during setback.
